[57] CLAIM

The ornamental design for an adapter housing for a video game control deck, as shown and described.

DESCRIPTION

FIG. 1 is a top and front perspective view of an adapter housing for a video game control deck showing our new design;

FIG. 2 is a front elevation view thereof;

FIG. 3 is left side elevation thereof;

FIG. 4 is a top plan view thereof;

FIG. 5 is a top and rear perspective view thereof;

FIG. 6 is a rear elevation thereof; and

FIG. 7 is a bottom plan view thereof.

The broken line showing of a video game control deck in FIG. 1 is for illustrative purposes only and forms no part of the claimed design.

Fig. 3.
